JOHANNES STICH, OF BERLIN-SIEMENSSTADT, GERMANY, ASSIGNOR TO SIEMENS & HALSKE AKTIENGESELLSCHAFT OF WERNERWERK, OF SIEMENSSTADT NEAR BERLIN, GERMANY

AUTOMATIC TELEPHONE SYSTEM

Application filed February 19, 1932, Serial No. 594,066, and in Germany March 2, 1931.

The present invention relates to a circuit arrangement for telephone systems with automatic operation and has for its object increased economy of such systems. This, according to the invention, is achieved by using the devices which transmit impulses also to cut off the ringing current.

An embodiment of the present invention is shown in the drawing. The subject matter relates to a private branch exchange in which a subscriber is able to connect himself automatically to the exchange line AL over the shown group selector GW, and in which incoming calls from the exchange, over the exchange line AL, are passed on by an operator to the required subscriber. In the arrangement shown, relay S serves in outgoing connections as an impulse repeater but operates as a ringing current cut off relay in the case of incoming calls.

When, for example, the exchange line AL is seized over the group selector GW by a subscriber associated with the private branch exchange, relay C is energized over switch wiper *c* of the group selector GW, and by the actuation of its contacts 1*c* and 2*c* disconnects the lines 3 and 4 from the exchange line AL. At the seizure of the exchange line AL, relay S is energized in known manner over: earth, battery, contacts 27*c*, 5*v1*, winding I of relay S, switch wiper *a* of the group selector GW, over the not shown subscriber's line loop, switch wiper *b* of the group selector GW, winding III of relay S, earth. Relay S closes contact 7*s* with the result that a switching device is seized over the exchange line by completing the loop over the *a*-lead of the exchange line AL, contacts 8A, 7*s*, choke Dr, contact 9A, *b*-lead of the exchange line AL. Relay V1 is energized by the opening of contact 6*s* and the closing of contact 10*s* over earth, contact 10*s*, relay V1 battery, earth and, upon closing its contact 11*v1*, sets up the following circuit: earth, contact 11*v1*, relay V2, relay V1, battery, earth. Relay V2 is not energized in this circuit. Relay V1 causes contact 5*v1* to be opened. This removes the short-circuit for winding II of relay S. If the subscriber now sends out impulses with the object of setting the switches

in the exchange, relay S will be cut off from battery at the first interruption at the subscriber's station. Contact 7*s* is reopened and breaks the loop referred to above which extends over the choke Dr. In addition, on the first release of relay S, contact 10*s* will be opened and contact 6*s* closed, causing relay V2 to be energized over: earth, contact 11*v1*, relay V2, contact 6*s*, battery, earth. Relay V2 opens contacts 12*v2* and 13*v2*.

The closing of contact 6*s* causes relay V1 to be short-circuited. The said relay V1, however, is not deenergized thereby since it remains energized due to the short-circuit and to the fact that it is constructed as a slow acting relay, until the circuit is re-closed after the impulse interruption, causing relay S to be re-energized. Relay S removes the short-circuit for relay V1 by opening contact 6*s*, with the result that relay V1 is connected to battery afresh by the closing of contact 10*s*. The closing of contact 10*s* short-circuits relay V2. This relay V2 also is a slow-acting relay and is not de-energized in the short interval in which relay S is energized during the circuit breaking at the subscriber's station. Relay V2, as well as relay V1, therefore, remains energized during an impulse series.

The circuit interruptions at the subscriber's station are transmitted by contact 7*s* to the exchange devices over the exchange line AL in the manner referred to above. Relay S is permanently re-energized at the end of the impulse series, with the consequence that the short circuit for relay V2 is maintained an extended period, causing the release of relay V2. Relay V1 also is maintained energized over: earth, contact 10*s*, relay V1, battery, earth, after the impulse series has ended.

The release of the device after the conversation is finished is effected in known manner and is of no interest in this case.

When a call is transmitted over the exchange line from the exchange, relay AR will be energized in known manner by the ringing current from the exchange which sets up a locking circuit over winding II of relay AR at the closing of contact 14*ar* and, at the

same time, lights up the signal lamp SL, connected in parallel to winding II of relay AR. The operator is heard after she has thrown her enquiry key, the contacts of which are represented by A in the drawing. The operator's instrument BA is connected to the exchange line AL by the throwing over of this enquiry key, due to contacts 8A and 9A being opened and contacts 15A and 10A closed. In 10 addition, the locking circuit over winding II of relay AR and the circuit for the signal lamp AL are cut off by opening contact 17A, and the circuit for relay P is prepared, at the same time, when contact 18A is closed. The 15 operator receives the calling exchange subscriber's instructions, who for example, wishes to set up a connection with a subscriber to be reached over the line TL. The operator then inserts the plug St in the subscriber's 20 jack TKL, which energizes relay P over earth, battery, resistance W, sleeve of the subscriber's jack TKL, contact 19 of the plug St, windings I and II of relay P, contact 18A, earth. Relay P energizes and locks itself up over winding I at contact 20p and at contact 28p it opens the circuit for relay C to prevent the exchange line AL from being seized by a group selector, such as GW. The ringing 25 current from the inductor RM is sent to the subscriber by the closing of contact 21p and takes the following path: inductor RM, contacts 21p, 5v1, winding I of relay S, contact 2c, line 4, contact 22 of plug St, contact 30 23 of jack TKL, a-lead of the subscriber's line TL, contact 24 of jack TKL, contact 25 of plug St, line 3, contact 1c, winding III of relay S, earth. When the called subscriber 35 answers, relay S is energized in the above mentioned circuit in a ringing pause during which a direct current battery is connected up instead of the inductor RM. Relay S causes relay V1 to be energized over: earth, battery, relay V1, contact 10s, earth, by opening 40 contact 6s and closing contact 10s. The opening of contact 5v1 breaks the ringing current circuit, whereas relay S, by the closing of contact 26v1 is maintained energized over: earth, battery, contact 26v1, windings 45 II and I of relay S, contact 1c, winding III of relay S, earth. The release of the connection is carried out in a manner which is 50 of no interest in this particular case.

As will be appreciated from the above, relay S is first used as an impulse repeating relay for outgoing calls whereas, in the case of incoming exchange connections, it operates as a ringing current cut off relay. The subject 55 matter of the present invention, however, is not restricted to the embodiment only in which the relay is used as an impulse repeating relay for outgoing calls and as a ringing current cut off relay in the case of incoming 60 connections.

What is claimed is:

1. In an automatic telephone system, a two-way trunk line, a relay associated with one end of said trunk line adapted to operate as an impulse-repeating relay in calls in one direction and as a ring-cut-off relay in calls in the opposite direction, and subscriber controlled means for operating said relay. 70
2. In an automatic telephone system, a two-way trunk line, and means connected to one end of the trunk operated by a calling subscriber to repeat impulses over the trunk line on outgoing calls and operated by an answering subscriber on incoming calls to disconnect signalling current. 75
3. In an automatic telephone system, a two-way trunk line extending from a branch exchange to a main exchange, a relay connected to said trunk line at the branch exchange end for repeating impulses to operate switches in the main exchange, an operator's position at the branch exchange for answering calls from the main exchange and for extending the same to the wanted branch exchange subscriber, and means responsive to removal of the receiver by the wanted subscriber for operating said impulse repeating relay to disconnect the ringing current used for signalling. 80
4. In an automatic telephone system, a two-way trunk line, a relay bridged across the conductors of said trunk line, means controlled by a calling subscriber for operating said relay to repeat impulses to operate automatic switches at the distant end of said trunk line, means for connecting ringing current to signal a wanted subscriber when a call is received from the distant end of said trunk line, means responsive to the removal of the receiver by the wanted subscriber for completing a circuit over the conductors of said trunk line to operate said relay, and means responsive to the operation of said relay for disconnecting said ringing current. 85
5. In an automatic telephone system, a two-way trunk line, a relay associated with one end of said trunk line, means controlled by a calling subscriber for operating said relay to repeat impulses on outgoing calls, and means responsive to the removal of the receiver by a wanted subscriber on incoming calls for operating said relay as a ring-cut-off relay. 90

In witness whereof, I hereunto subscribe my name this 19th day of January, A. D. 1932.

JOHANNES STICH.
